UNITED STATES PATENT OFFICE.

OSCAR PATRICK, OF SPRINGFIELD, OHIO.

DESIGN FOR A HANDLE FOR CANES AND UMBRELLAS.

43,409.

Specification for Design.

Patented Dec. 31, 1912.

Application filed August 26, 1912. Serial No. 717,226. Term of patent 14 years.

To all whom it may concern:

Be it known that I, OSCAR PATRICK, a citizen of the United States, residing at Springfield, in the county of Clark and State of Ohio, have invented a new, original, and ornamental Design for Handles for Canes and Umbrellas, of which the following is a specification, reference being had to the accompanying drawing, forming a part thereof.

The figure is a side view of a handle for a cane or umbrella, showing my new design.

I claim:

The ornamental design for a handle for canes and umbrellas, as shown.

OSCAR PATRICK.

Witnesses:

GEORGE W. TEHAN,
NELLIE C. TEHAN.
